DEFLECTION COIL ARRANGEMENT FOR
CATHODE RAY TUBES

Rudolf Urtel, Pforzheim, Germany, assignor to International Standard Electric Corporation, New York, N. Y., a corporation of Delaware

Application June 27, 1952, Serial No. 295,946

Claims priority, application Germany June 29, 1951

3 Claims. (Cl. 317—200)

This invention relates to deflection coils and more particularly to deflection coil windings suitable for use in reproduction cathode ray tubes for television receivers.

Deflection coil systems of two principal types are generally known for use in controlling the deflection of cathode ray beams. In one of these types the windings of the coil are such that a relatively weak external field is produced on this type. Also it has the disadvantage that at both ends of the deflection coil system the control field extends on a small distance from the end of the deflection coil arrangement. This small distance of extension is helpful on the cathode end of the tube in that it does not produce unwanted eddy currents, which may tend to disturb the function of the beam. On the other hand, it is a disadvantage in that the control does not extend any appreciable distance beyond the coil in the direction of the reproduction screen.

A second well known form of deflection system is provided wherein the deflection windings provide closed rings about an annular core. With this type of arrangement there is a considerable external field and the deflection field itself extends a substantial distance from both ends of the deflection system. This has the advantage of greater control of the beam in the direction of the screen but the disadvantage that the eddy currents are set up in the cathode and through portions of the system. These eddy currents may produce detrimental effects.

According to this invention there is provided a deflection coil system which has the advantage of producing a substantially extending field in the direction of electron beam control and a rapidly decaying field in the direction of the cathode and other electrodes.

Accordingly, it is an object of this invention to provide a deflection coil system for cathode ray tubes in which the windings on an annular core are arranged so that at one end of the core a portion of the windings produces an extended longitudinal deflection field on the axis of the core and at the other end a rapidly decaying of the deflection field is produced by another portion of the windings.

The above-mentioned and other features and objects of this invention and the manner of attaining them will become more apparent and the invention itself will be best understood by reference to the following description of an embodiment of the invention taken in conjunction with the accompanying drawings, in which

Figs. 1 and 1a show a diagrammatic perspective and a diagrammatic longitudinal section illustrating the well known form of coil winding and the field produced thereby respectively;

Figs. 2 and 2a illustrate a second known form of deflection coil and deflecting pattern similar to those of Fig. 1;

Figs. 3 and 3a show diagrammatic perspective and a longitudinal section similar to Figs. 1 and 2;

Figs. 4 and 4a illustrate an alternative winding arrangement and field pattern system similar to that shown in Fig. 3.

2

Two principal shapes of windings are known for the deflection of the cathode ray beam in television tubes. The first shape of windings is known as the so-called shell-core coil, the coils of which consist of individual coil-packs 1 and 2 with closed windings, and in which those winding components, not contributing to the deflection, proceed in a plane perpendicular to the tube axis and partly embrace the neck of the tube. The iron core 1a of the winding embraces the coils as a shell. Such a coil arrangement with its field line pattern is shown in Figs. 1 and 1a. The advantage of this shape of coil is that it exhibits a weak external field which will produce only small eddy currents in the neighboring parts, such as the axial focussing coil, the magnet and/or the shieldings. The field lines cross each other in the plane through the axis in field direction at the saddle point S closely in front of the coil, so that a rapidly decaying field is formed in axial direction. On the end of the coil adjacent the cathode this quickly decaying field has the advantage of a small coupling of eddy current, on the screen-sided end of the coil, however, the disadvantage that the extension of the field is small in the useful direction. Another drawback of this kind of coils is the poor optico-electronical quality.

The second shape of windings is known as the so-called ring-core coil, consisting of an iron yoke body embracing the ray and of windings 3 and 4 embracing the cross-section of this yoke. Such a coil arrangement with its field lines is represented in Figs. 2 and 2a. This shape of coil is featured by an axially expanded field in useful direction, because the saddle points fall away. Optically the coil is good, but has the disadvantage that the extended field in the axial direction causes, on the cathode end, more extensive eddy currents with the focussing device. Also the currents energize a strong outer field in the outer winding parts, which again causes a greater coupling of eddy currents to the shielding.

The deflecting coil arrangement according to the invention is characterized by such a form of windings that the features of the ring-core winding, extended field in useful direction, strong outer field, are combined with the features of the shell-core winding (quickly decaying field in axial direction, weak outer field).

Some embodiments of the deflecting coil arrangement according to the invention are represented in the Figs. 3 to 6 of the drawing.

In each of these examples only one set of deflection windings is illustrated since the showing of both sides of deflection windings would render the illustration confusing. It may be considered that the windings as illustrated in these figures correspond to other vertical or horizontal section windings of a television receiver cathode ray tube. It will be clearly understood that the other set of windings would be arranged on the core at 90° spacing to the windings shown here and will serve for the co-ordinate deflection.

As pointed out already, it is desired to generate an extended useful field in direction of the screen and to have a quickly decaying field in the direction of the cathode, in order to keep the eddy currents in the focusing equipment as small as possible and furthermore, if possible, to keep the external field small also.

An example for achieving this field distribution is represented in Fig. 3. Within the iron core 5 a shell-core winding 6 is provided. At one end of the windings the wire thereof is bent back so the cross-connection 7 overlies the end as shown. By this arrangement the winding components which do not contribute to the deflection are spaced from the front of the core and the saddle point S of the field lines of the winding is removed outwards on this side of the coil and thereby the field is extended in useful direction. In this way one obtains a coil, which produces on the screen side of the winding an extended

field in useful direction, similar to the ring-core coil, but which has a quickly decaying field in axial direction on the cathode side of the winding, similar to the actual shell-core coil of Fig. 1. Moreover, the part of the winding spaced from the end weakens the outer field, as may be seen from the field line pattern, thus weakening the eddy currents in the shielding.

In Figs. 4 and 4a is illustrated another embodiment of the deflection coil arrangement similar to that shown in Fig. 2. However, in this arrangement the other end 8 of the winding is also bent back so that its cross-connector 8 also overlies the end of the core as shown. This cross-connector 8 may be arranged to be near the end of the core so that it will also have some influence on the extension of the deflection field in this direction. However, the spacing between the cross connectors 7 and 8 may be adjusted to give the desired control to the field longitudinally of the core and winding. It will be realised that the longitudinal extension external of the core will have a similar effect on the deflection to that produced by the ring of windings shown in Fig. 2, but will be modified by the cross connections similar to the known form of Fig. 1 to a controllable extent. Thus, there can be provided with this system an adjustable control of the extension of the field longitudinally of the axis of the deflection system. At the same time, the external field due to the windings radially of the axis is considerably reduced.

While I have described above the principles of my invention in connection with specific apparatus, it is to be clearly understood that this description is made only by way of example and not as a limitation to the scope of my invention as set forth in the objects thereof and in the accompanying claims.

What is claimed is:

1. In a deflection coil system for cathode ray tubes for producing an extended control field axially of the coil system at one end thereof, and a quickly decaying field axially of said coil system at the other end thereof, the

combination comprising a closed hollow cylindrical core of magnetic material, and a winding on said core for producing deflection fields, said winding having a first portion comprising wires extending longitudinally internally of said core, a second portion adjacent one end of said core and extending substantially circumferentially and externally thereof for interconnecting said wires, said second portion being positioned intermediate the ends of said core, to provide a substantial extension of said deflection fields axially of said core, and a third portion adjacent a second end of said core and extending substantially circumferentially of the axis and externally to produce a rapid decay of said deflection fields axially of said core.

2. In a deflection coil system according to claim 1, the combination wherein said second portion comprises an interconnecting wire arranged on the outer surface of said core and spaced from one end thereof, the ends of said interconnecting wire extending substantially parallel to the axis of said core and being connected to said longitudinal wires.

3. In a deflection coil system according to claim 2, the combination wherein said third portion comprises a wire extending about the outer surface of said core traversely of the axis and spaced a distance from the other end less than the spacing of said second portion from its corresponding end and having its opposite ends extending substantially parallel to said axis and connected to said longitudinal wires.
